UNITED STATES PATENT OFFICE

JOHN R. ROGERS, OF BROOKLYN, NEW YORK, ASSIGNOR TO MERGENTHALER LINOTYPE COMPANY, A CORPORATION OF NEW YORK

TYPOGRAPHICAL COMPOSING MACHINE

Application filed August 26, 1931. Serial No. 559,434.

This invention relates to typographical composing machines, such as linotype machines of the general organization represented in United States Letters Patent No. 436,532 to O. Mergenthaler, wherein circulating matrices are released from a magazine in the order in which their characters are to appear in print and then assembled in line, the composed line transferred to the face of a slotted mold, the mold filled with molten metal to form a slug or type-bar against the matrices which produce the type characters thereon, and the matrices thereafter returned through distributing mechanism to the magazine from which they started.

More particularly it relates to that class of machines (see for instance U. S. Patent No. 1,397,974 to Kennedy) designed to handle matrix fonts which differ from one another in the size and number of characters, as, for example, the ordinary or ninety character fonts used for the composition of "straight matter", and the special seventy-two or fifty-five character fonts used for the composition of head letter or display matter.

The present invention is directed to an improved assembler entrance for machines of the class stated and one which is equipped with a plurality of interchangeable throat sections differing as to form to correspond to the respective magazines. In the preferred embodiment illustrated, the interchanging of the magazines and the throat sections is effected simultaneously, or at one operation, the selection of the proper throat section for cooperation with the magazine brought into active position being accomplished automatically by means of operative connections between the throat sections and the magazines, so as instantly to adapt the assembler entrance to handle an ordinary font or a display font as may be required.

In the accompanying drawings, the invention has been shown in connection with a shiftable multiple magazine machine such as that illustrated in U. S. Letters Patent No. 1,109,872 to Rogers, but it is equally applicable to machines of other kinds including those equipped with a single magazine.

In other words, the improvements are shown merely in preferred form and by way of example and obviously many changes and modifications may be made therein which will still be comprised within its spirit. It is to be understood therefore that the invention is not limited to any specific form or embodiment except insofar as such limitations are specified in the appended claims.

In the drawings:

Fig. 1 is a side elevation of a portion of a linotype machine equipped with the present improvements, and showing the lower throat section in action;

Fig. 2 is a top plan view of the parts shown in Fig. 1;

Fig. 3 is an enlarged vertical section showing the upper throat section in action;

Fig. 4 is a front perspective view, showing the throat sections in process of removal from the machine; and

Figs. 5 and 6 are plan views, partly in section, showing, the partition plates of one throat section cooperating with matrix columns of a seventy-two character font and the partition plates of the other section cooperating with matrix columns of a ninety character font, respectively.

The several magazines are carried by a shift frame A, composed in part of the two swinging base frames A¹, arranged to be raised and lowered in the well-known manner so as to bring any selected one of the magazines into operative position. As herein indicated, the two lower magazines B are of regular form, each being provided with ninety-one grooved channels spaced apart in the usual way to adapt them to contain an ordinary ninety character matrix font; whereas the top magazine C is of special form, being provided with only seventy-three grooved channels spaced apart in a different manner to adapt them to contain a seventy-two character display font.

When the magazines are shifted to bring a ninety character font into use, the regular distributor bar and magazine entrance are employed for returning the matrices to their magazine, but when the magazines are shifted to bring a seventy-two character font into

use, a special distributor bar and magazine entrance are employed to cooperate therewith. Since this feature forms no part of the present invention, it need not be further 5 discussed, but if more detailed information is desired, it can be found in the Kennedy Patent No. 1,397,974 already referred to or in the Rogers Patent No. 1,661,504.

The improved assembler entrance, the upper 10 portion only of which is shown in the several figures, presents a main section D made up, as usual, of a front cover plate d, a back plate d', and a series of intervening upright matrix guides or partition plates d², such parts being shorter than heretofore or 15 cut away at the top so as to accommodate a pair of throat sections E and E'.

In the preferred embodiment illustrated, the throat sections E and E' are disposed 20 in superposed relation and are slideable upwardly and downwardly as a unit for interchange, being provided at opposite ends with V-shaped tongues e' (see Fig. 4) adapted to fit in correspondingly shaped guideways e², 25 these guideways being formed in brackets F and F' secured to the fixed frame of the machine by bolts f' and f².

The throat unit is moved upwardly to bring the lower section E into proper alignment 30 with the fixed section D, being arrested in such alignment by a pair of set screws j and j' carried by the brackets F and F' respectively; and, conversely, it is moved downwardly to bring the upper section E' 35 into alignment with the fixed section D, being arrested in such alignment by a second pair of set screws j² and j³ also carried by the brackets F and F'.

Retaining plates G and G', pivoted at one 40 end to the brackets F and F' and slotted at the other end to receive fastening studs g and g' having thumb nuts g² and g³, are adapted to retain the throat sections in the supporting frames F and F' or to permit 45 their removal from the machine.

As will be noted, the throat unit comprises a pair of end walls L, two base plates H and H' fastened thereto, and two series of vertically disposed partition plates h anchored 50 securely to the base plates H and H'. The base plate H' of the upper section E' serves as a cover plate for the lower section E, but instead of a rigid cover plate for the upper section, there is provided a movable matrix 55 guide K, pivoted as at k to the end plates L, and bevelled on its under surface to facilitate the guiding of the matrices as they enter the upper section.

Fig. 1 shows the lower throat section E in 60 operative relation to a regular ninety-one channelled magazine, while Fig. 3 shows the upper throat section E' in operative relation to a special or seventy-three channelled magazine. As will be noted, (see also Figs. 65 5 and 6) the lower ends of the partition

plates h of both throat sections register with the upper ends of the partition plates d² of the main section D of the assembler entrance, but since the lower throat section cooperates with a ninety-one channelled magazine, and the upper throat section cooperates with a seventy-three channelled magazine, the spacing of the upper ends of the partition plates h differs in the respective sections. In other words, when the throat section E is in use, its partition plates h will be disposed at certain angles from the points of registration with the main partition plates d² to handle matrices M of the ordinary fonts; whereas, when the throat section E' is in use, altho its partition plates h will also register with the main partition plates d², they are disposed at different angles from such points of registration to serve in like manner to handle matrices M' of the display fonts.

While it is obvious that the throat unit might be operated manually in effecting the interchange of its two sections, it is proposed, according to the present invention, to couple the unit with the magazines in such manner that an interchange of magazines will automatically bring about a corresponding interchange of the throat sections. Further, since it is common practice to mount two regular magazines and a special magazine one above the other on the machine with the special magazine uppermost, it is proposed to utilize a flexible or yielding coupling which will permit an interchange of the throat sections only when an interchange is made between a ninety character font and a seventy-two character font or vice versa.

To the end stated (Figs. 1, 2 and 4), the throat unit is provided at its opposite ends with a pair of bracket arms S, formed with cylindrical bosses s thru which are passed rods s'. These rods s' are formed at their lower ends with collars s², retaining between them and the bosses s compression springs s³, and the upper ends of the rods are hook-shaped, as at s⁴, to adapt them for detachable engagement with projecting plates N secured to the base frame A' of the middle magazine. To prevent the rotation of the rods s' about their longitudinal axes (which would move their hooked ends out of alignment with the plates N), each rod is formed with a longitudinal groove s⁵, in which a detent, having a knob S' and being arranged in the wall of the boss s, is adapted to ride. However, when it is desired to disengage the rods s' from the plates N so as to break the connection between the throat sections and the magazines, it may be accomplished merely by pulling outwardly on the knobs S' to retract the detents from the grooves s⁵ and rotating the rods s' manually.

As a result of the foregoing arrangement, when the lowermost ninety character mag-

azine is in operative position (Fig. 1), the rods s' , due to their engagement with the plates N , are pulled upwardly and compress the springs s^3 , which consequently act thru 5 the brackets S to hold the throat unit in its upper position, thereby alining the lower section E with the magazine on the one hand and the fixed section D of the assembler entrance on the other hand. The downward 10 shifting of the magazines to bring the middle or the other ninety character magazine into operative position lowers the rods s' , and allows the compression springs s^3 to expand; nevertheless, when the magazine is 15 located in operative position, the tension of the springs s^3 is still sufficient to hold the throat unit in its raised position, so that the lower section E will remain in alinement with the fixed section D of the assembler 20 entrance, and will of course be brought into alinement with the newly selected magazine by virtue of its movement into operative position. However, when the magazines are lowered still further to bring the uppermost 25 or seventy-two character magazine into operative position, the springs s^3 lose their tension completely, and the throat unit falls by gravity to the lower position shown in Fig. 3 to bring the upper section E' into 30 alinement with the newly selected magazine and the fixed section D of the assembler entrance.

The front cover d of the assembler D is customarily made of glass (at least its upper part) and is pivotally supported as at d^4 and d^5 on the brackets F and F' ; hence, it can be determined at a glance whether or not the proper throat section is in place by noting the alinement of the partitions 40 thereof with the channel walls or ribs o of the magazines (see Figs. 5 and 6) or with the partition plates d^2 of the fixed section D . Further, any disorder occuring in the throat sections or at the discharge end of 45 the magazine can be readily seen, and may be easily and quickly remedied, since access may be had to the parts by merely raising the guide K , the glass cover d , or both; and if necessary, the whole throat unit may be 50 readily removed as illustrated in Fig. 4.

Having thus described my invention, what I claim is:

1. In or for a typographical composing machine, an assembler entrance comprising a fixed partitioned main section, and a plurality of partitioned throat sections facing in the same direction and, said throat sections being movable bodily with reference to the main section to bring a selected throat 55 section into alinement with the main section.
2. In or for a typographical composing machine, an assembler entrance comprising a fixed main section provided with partition plates, and a plurality of throat section 60 equipped with differently located partition

plates, said throat sections being disposed side by side and facing in the same direction and being movable bodily transversely of the main section to bring a selected throat section into alinement with the main 70 section.

3. In or for a typographical composing machine, an assembler entrance comprising an upright main section provided with partition plates, and a pair of superposed parallel throat sections equipped with differently located partition plates, said throat sections facing in the same direction and being slideable as a unit upwardly and downwardly 75 to bring either one into alinement with the fixed section.

4. In or for a typographical composing machine, an assembler entrance provided with two superposed parallel throat sections facing in the same direction and equipped with differently located partition plates and slideable upwardly and downwardly as a unit for interchange. 80

5. In or for a typographical composing machine, an assembler entrance provided 90 with a slideable two-section throat unit composed of two parallel base plates and two series of partition plates fixed to the respective base plates, the partition plates of both series facing in the same direction but those of one series being located differently from those of the other series.

6. An assembler entrance as recited in claim 3, characterized by the fact that the upper throat section is provided with an upwardly yielding matrix guide. 100

7. An assembler entrance as recited in claim 5, characterized by the fact that one of the base plates forms a dividing partition between the two sections. 105

8. An assembler entrance as recited in claim 2, characterized by the fact that the throat sections are removable as a unit from the machine.

9. In a typographical composing machine, the combination of a plurality of magazines of different forms shiftable to bring a selected one thereof into active position, an assembler entrance having a plurality of throat sections differing as to form and movably mounted for interchange, and means whereby the selection of a magazine automatically effects the selection of the corresponding throat section for cooperation therewith. 110

10. In a typographical composing machine, the combination of a plurality of magazines of different forms shiftable to bring a selected one thereof into active position, an assembler entrance having a plurality of throat sections differing as to form and movably mounted for interchange, and operative connections between the magazines and the throat sections whereby the selection of a magazine automatically 115 120 125 130

effects the selection of the corresponding throat section for cooperation therewith.

11. In a typographical composing machine adapted to be equipped with differently formed magazines interchangeable in operative position with one another, an assembler entrance having differently formed throat sections movably mounted for interchange, and automatic means whereby the selection of a magazine effects the selection of the corresponding throat section for cooperation therewith.

12. In a typographical composing machine, the combination of three magazines movably mounted for interchange, two of the magazines being alike as to form and the other of different form, an assembler entrance having two movably mounted throat sections, one of which is adapted to cooperate with the two like magazines and the other of which is adapted to cooperate with the third magazine, and operative connections between the magazines and the throat sections whereby one section or the other is brought into use according to the magazine selected.

13. In a typographical composing machine, the combination of three magazines movably mounted for interchange, two of the magazines being alike as to form and the other of different form, an assembler entrance having two movably mounted throat sections, one of which is adapted to cooperate with the two like magazines and the other of which is adapted to cooperate with the third magazine, and a yielding connection between the throat sections and the magazines whereby the corresponding throat section is held in active position when the magazines are moved to interchange the two like magazines, said connection permitting the movement of the other throat section into active position when an interchange is made between one of the two like magazines and the third magazine.

14. A combination as in claim 12 wherein the three magazines are arranged one above the other, the third magazine being topmost, and wherein the operative connections are between the throat sections and the middle magazine or its supporting frame.

15. A combination as in claim 12, wherein the three magazines are arranged one above the other with the third magazine topmost, and wherein the throat sections are provided at each side of the machine with a bracket formed with a boss having a cylindrical bore thru which is passed a rod, one end of which is hook-shaped and adapted to engage a plate secured to the intermediate magazine base frame.

16. A combination as in claim 12, wherein the three magazines are arranged one above the other with the third magazine topmost, and wherein the throat sections are pro-

vided at each side of the machine with a bracket formed with a boss having a cylindrical bore thru which is passed a rod, one end of which is hook-shaped and adapted to engage a plate secured to the intermediate magazine base frame, and the other end of which is formed with a collar adapted to retain a compression spring on the rod between it and the bracket boss, whereby the connection between the throat sections and the magazines is rendered flexible.

17. A combination as in claim 9, characterized by the fact that the throat sections are provided at each side of the machine with a tongue adapted to slide in a guideway formed in a support secured to the frame of the machine, and further characterized by the fact that a hinged plate is arranged to be fastened over each guideway to retain the throat sections in the supports or to permit their removal therefrom.

18. A combination as in claim 9, wherein two pairs of adjusting screws are provided to arrest the throat sections in their different positions and aline the active section with the magazine with which it is adapted to cooperate.

19. In a typographical composing machine, the combination of a plurality of magazines differing as to form and movable upwardly and downwardly to bring one or another into active position, an assembler entrance comprising a fixed partitioned main section and a plurality of differently partitioned throat sections movable upwardly and downwardly to bring one or another into alinement with the main section, and means whereby the movement of the magazines effects the movement of the throat sections such that the selection of a magazine will effect the selection of a corresponding throat section.

20. In a typographical composing machine, the combination of a plurality of magazines differing as to form, means for selecting one or another of the magazines for use, an assembler entrance comprising a fixed main section and a plurality of throat sections differing as to form to correspond to the magazines, means for alining one or another of the throat sections with the main section, and automatic means whereby the selection of a magazine effects the selection of the corresponding throat section.

In testimony whereof, this specification has been duly signed by:

JOHN R. ROGERS.
